Primary Examiner — Rachel A. Voorhies(74) *Attorney, Agent, or Firm* — Morgan, Lewis & Bockius LLP(57) **CLAIM**

The ornamental design for a ventilator display screen with graphical user interface as shown and described.

DESCRIPTION

The FIGURE is a front view of an image for a ventilator display screen with graphical user interface showing our new design.

The peripheral dash-dot-dash lines illustrate a ventilator display screen or portion thereof and form no part of the claimed design. The broken lines within the peripheral dash-dot-dash lines illustrate portions of the ventilator display screen with graphical user interface, which form no part of the claimed design.
